UNITED STATES PATENT OFFICE

1,973,645

FOUNDATION AND ATTIC VENTILATOR

Christopher G. McGilvray, Tulsa, Okla.

Application October 12, 1933, Serial No. 693,345

1 Claim. (Cl. 98—88)

This invention relates to an improved ventilator structure for incorporation in building and construction walls and it has more particular reference to a type or form of ventilator which is particularly adapted for foundation and attic insulation.

In order to promote health and well being of individuals occupying buildings and houses, I have discovered what I believe to be the need for a simple and economical ventilator which may be installed in a foundation, for example, to ventilate the space between the lower structure of a house and the ground to dispel musty air and eradicate termites and other pests and insects.

In reducing the preferred embodiment of the invention to actual practice, I have adopted and utilized a frame including a duplex grille or grid assembly, together with a pair of interiorly located imperforate cover plates for the grille, said cover plates being adjustably mounted on the frame structure so that they can be effectively closed to prevent circulation of air or swung to open position to deflect and promote adequate circulation of air for ventilating purposes.

Other features and advantages will become more readily apparent from the following description and drawings.

30 In the drawings:—

Figure 1 is an inside elevational view of the arrangement, showing the cover plates in closed positions.

Figure 2 is an exterior or outside view of the arrangement seen in Figure 1.

Figure 3 is a view in section and elevation, disclosing the assemblage and showing the cover plates swung to open air circulating positions in full lines and occupying closed positions in dotted lines.

40 In the drawings, in Figure 3 for example, the building wall is differentiated by the letter A and the window opening by the letter B. It is in the opening B that the entire device, as a unit, is installed or mounted. As before implied, it comprises a grille unit 4, here shown as comprising a suitable marginal metallic frame 5 centrally divided into upper and lower sights, each covered with an open-work grid or screen 6. A cover plate is provided for each grid and the cover plates are the same in construction and a description of one will suffice for both. Each cover plate is denoted by the numeral 7 and it comprises a substantially rectangular 55 pan-shaped closure of imperforate design, the

depth of the pan being such that it serves to accommodate the expanding and contracting linkage. A pair of hinge and supporting links 8 is provided and pivotally connected at the outer ends, as at 9, to the marginal rim of the 60 pan-like cover. The inner ends are pivotally attached, as at 10, to the grille frame. The numerals 11 designate arcuate slotted stay links, each link being pivotally attached at its outer end, as at 12, to the cover and the inner end 65 thereof having slidable engagement with a screw threaded stud carrying a thumb nut 13. The stay link is projectable through one of the openings in the mesh of the screen and, therefore, permitted to occupy either the full or dotted 70 line position shown in Figure 3. By attaching the stay links 11 to the lower portion of the cover, it moves the cover down in the proper arc to effective closed position. They also operate in unison with the hinge or supporting links 8. 75 The link 8 is merely a straight link and somewhat shorter than the curved link 11. By properly proportioning and attaching the two pairs of links with respect to the cover, when the cover is in open position, it occupies an angular position and when the two cover plates are swung out, they assume outwardly converging spaced 80 relationship to function as deflectors. Thus the air is permitted to circulate freely when the covers are open and when the covers are closed, 85 they afford the requisite tight closing action for cold and inclement weather.

It may be added that the numerals 14 merely designate handles or finger grips which can be made sufficiently large to facilitate gripping or 90 can be made in the form of small hooks so that they can be conveniently operated with a reach rod or similar implement (not shown). As before stated, the ventilator is usable in an attic as 95 well as in cellar construction and means must, therefore, be provided for convenient operation from a remote point.

It is within the conception of the invention to make the structure of a double or duplex type 100 or of a single type, and the following claim is to be interpreted accordingly.

It is thought that the description, taken in connection with the drawings, will enable a clear 105 understanding of the invention to be had. Therefore, a more lengthy description is thought unnecessary.

While the preferred embodiment of the invention has been shown and described, it is to 110 be understood that minor changes coming with-

in the field of invention claimed may be resorted to if desired.

I claim:—

5 A device of the class described comprising a frame for fitting in a window or other opening, upper and lower pan-shaped plates, slotted links connecting each plate to the frame, said links being pivoted to the frame and the links for the upper plate being pivoted to said plate above 10 the horizontal center of the plate and the links for the lower plate being pivoted to said plate

below the horizontal center thereof, arcuate-shaped links having longitudinally extending slots therein for adjustably connecting the plates to the frame, screws passing through the slots of said links into the frame, the slotted links which are connected with the upper plate being connected to the lower end of said plate and the slotted links which are connected with the lower plate being connected to the upper end of said plate. 80
